UNITED STATES PATENT OFFICE

EMIL ACKERMAN, OF CHICAGO, ILLINOIS

AIR CIRCULATING DEVICE FOR HOT AIR FURNACES

Application filed January 8, 1929. Serial No. 331,037.

The present invention relates to improvements in air circulating devices for warm air furnaces, and relates more particularly to the provision of a device, adapted to be mounted in the cold air intake of a warm air furnace, capable of creating a forced draft therethrough.

In various instances it is necessary to provide suitable means for artificially creating a forced draft in the various air passages of furnaces of the above named type in order that the full benefit of such a heating system may be attained.

Numerous means and various devices have been developed for creating such a draft in hot air furnaces but, until the development of the present invention, no suitable means, applicable to known types of hot air furnaces, has been perfected. Of the various devices previously developed, each is provided with means for checking the counteracting effect of a back pressure created within the air intake duct, by the forced draft passing therethrough. This means provided for the closing of auxiliary air passages in the air circulating device, the closing means commonly employing movable louvres actuated either by the direct draft or by the back pressure.

It can readily be appreciated that the employment of movable louvres in an air intake duct, especially when the actuation of said louvres is dependent upon forced draft or back pressure, does not provide a device which may be relied upon as being positive in operation. Any obstruction, such as, for example, small particles of dirt, lodging in the path of the air operated louvres which louvres must necessarily be very freely mounted, will tend to prevent their actuating, thus defeating the purpose thereof. Should the auxiliary air passages be left open, when the force draft creating means is in operation, the back pressure created in the air duct will cause such a circulation of air therein that no benefit will be derived from the device.

The foregoing recites but a few of the objectionable features which have been developed as the art of artificially creating a forced draft in hot air furnaces progressed,

and it is, therefore, one of the principal objects of the present invention to provide an air circulating device for hot air furnaces having means rigidly mounted therein for directing the flow of air through the entire device.

It is another object of this invention to provide a novel device for creating a forced draft in the air passages of a hot air furnace which will be noiseless and positive in operation, the means for creating the draft therein being resiliently mounted, thus eliminating undesirable noise normally set up by the vibration of such means.

Another object of the present invention resides in the provision of a device for creating a forced draft in the air passages of hot air furnace having but few moving parts and is therefore, inexpensive to manufacture and maintain.

These and such other objects as will appear hereinafter as the description proceeds will be more readily understood from the following specification, reference being had to the accompanying drawings, in which:

Fig. 1 is a perspective view of the improved air circulating device mounted in the intake duct of a furnace.

Fig. 2 is an elevational view of the device, as viewed from the air inlet side.

Fig. 3 is a horizontal central sectional view through the novel air circulating device, taken on line 3—3 of Fig. 2, having portions of the air intake duct attached thereto.

Fig. 4 is a fragmental elevational view similar to Fig. 2, of another form of the invention, showing a modified arrangement of louvres therein.

Fig. 5 is a fragmentary horizontal sectional view similar to Fig. 3, but showing a further modification of the invention.

The air circulating device shown in the drawings preferably comprises a frame member, having means for creating a forced draft mounted thereon, which provides a unitary structure for mounting within an air intake duct of a hot air furnace. This frame member comprises a substantially rectangular frame 11 formed of sheet metal and having

outwardly directed flanges 12 on each edge thereof to provide means for securing there-
to the flanged ends of the air intake duct 13,
of the furnace 14. Resiliently mounted on
5 the rectangular frame member 11, and ex-
tending rearwardly therefrom, is a blower
fan motor 15, said blower fan motor being
suitably mounted on a panel 16. The panel
10 is rigidly secured in any suitable manner
in the said rectangular frame member 11
midway the end walls thereof.

A centrally located opening 17 is provided
in the panel 16 to permit passage of a forced
draft therethrough, and mounted around
15 the circumference of said opening, at spaced
intervals, are a plurality of mounting arms
18, which mounting arms form means for
securing the motor 15 to said panel.

The blower fan motor 15 is preferably
20 secured to the mounting arms 18 in such a
manner that most all of the vibration set
up by said motor is absorbed thereby, thus
eliminating the noises created within the
device by such vibration. The mounting
25 means preferably employed for absorbing
the vibration of the motor, comprises a plu-
rality of spaced ears 19 on the housing of
the motor 15. Each of these ears is provided
with a threaded bore adapted to receive a
30 bolt 21, which bolt passes through an aper-
tured boss 22, provided therefor on the in-
turned end of each arm 18, and is threaded
into the apertured ear 19. Rubber or other
similar resilient material is preferably em-
35 ployed to provide washers 23, which are
placed over the bolts 21, on either side of
each of the apertured bosses 22, and a metal-
lic retaining washer 24 is placed on each of
said bolts beneath the head thereof. This
40 construction provides a very secure mount-
ing for the motor 18, as well as insulating it
therefrom to the extent that the vibration set
up by said motor is absorbed by the insula-
tion, thereby making the device extremely
45 quite in operation.

The motor shaft 25a extends inwardly a
short distance toward the panel 16 and has
rigidly mounted thereon a blower fan 25
which blower fan is preferably of a size suf-
50 ficiently large to cover the entire area of
the opening 17, in the panel.

As shown in the drawings, the panel 16 is
mounted near the inlet side of the rectangular
frame member 11 and as previously men-
55 tioned, is centrally located relative to the
vertical end walls of said frame to provide
an air passage on either side thereof. Flanges
26 are formed on each vertical edge of said
60 panel to add strength thereto, which flanges
are bent inwardly for a purpose to be de-
scribed later. Centrally located in the rec-
tangular frame member, adjacent the panel
65 16 is a baffle plate 27, said baffle plate being
formed substantially V shaped in cross sec-
tion and having its apex directed towards

and in vertical alignment with the blower
fan motor 15.

It will be readily understood, from Fig. 3,
that, when the blower fan 25 is in operation,
the draft created thereby is forced through
70 the opening 17, in the panel 16, and, the baffle
27 will deflect the said forced draft toward
each vertical side wall of the air intake
duct 13.

This means of deflecting the forced draft
75 will serve to prevent air being forced direct-
ly forward of the blower fan, thereby elimi-
nating back pressure along the side walls of
the intake duct, which back pressure causes
80 air to flow rearwardly through and beyond
the air circulating device. The circulation
of air set up by a back pressure of this nature
creates a continuous cycle of air in the vicin-
ity of said device, thereby defeating the pur-
85 pose of the forced draft.

Of course, additional means must be pro-
vided in the air passages to further aid the
counteraction of the air currents created by
the blower fan, as mere divergence of the
90 forced air draft towards the side walls of the
air duct, by the baffle plate 27, will not serve
to completely eliminate back pressure there-
in. This additional means is provided for
95 by the installation of a plurality of baffle
plates, or louvres, 28 in said air passages,
which baffle plates are also preferably V-
shaped in cross section, and are secured, in
a vertical position, to the top and bottom
100 walls of the rectangular frame member 11 by
the flanges 29, rigidly secured to said walls
by welding or, any other similar means may
be employed.

The baffle plates, or louvres, 28 preferably
have their apex disposed toward the center
105 of the air circulating device so that air
siphoned through the air passages by the
forced draft, will assume the same general di-
rection of the deflected forced draft, thereby
becoming a part thereof, as indicated by the
110 arrows in Fig. 3, rather than tending to
counteract the direction of said forced draft.

To provide a proper semi-closure for the
air passages, adjacent the end walls of the
frame 11, it is preferable to provide a ver-
115 tically disposed louvre 30, which is adapted
to be rigidly secured to the housing 11 and
extend inwardly a short distance from the
end walls thereof, as shown.

Of course, in such air circulating devices as
those described in the foregoing, complete
120 elimination of back pressure in the air duct
is practically impossible.

However, with the present device any back
pressure created in the air duct though very
small will be in the substantial center there-
of, that is: directly behind the baffle 27,
rather than along the side walls of the duct,
125 and as said back pressure strikes the baffle 27
air currents thereof will be deflected in either
direction into the path of the forced draft.

When the blower fan 25 is not in operation air may freely pass through the central opening 17 and through the air passages adjacent the panel 16. Thus at no time will a hot air heating system, employing the improved air circulating device, be deprived of a plentiful supply of fresh inflowing air, the baffle plates 28, being of such construction as to offer little or no resistance to the air siphoned therethrough by the forced draft.

10 In the form of the invention shown in Fig. 4, the centrally located vertically disposed V-shaped baffle plate employed in the preferred form of the invention is disposed of, and, mounted in place thereof is a substantially conical baffle member 31. This baffle member 31 is centrally supported, relative to the opening 17, in the panel 16, by a pair of oppositely disposed straps 32, which straps 20 are preferably riveted to the outside periphery of said baffle member and have their outer ends bent substantially at right angles, as shown, and secured to the top and bottom walls of the rectangular frame 11.

25 With a baffle of this type employed, air forced through the aperture 17, by the blower fan 25, will be directed towards all four walls of the air duct 13. Any back pressure created within the duct will cause air currents to flow rearwardly at the substantial central portion thereof, that is; directly behind the conical member, whereupon when reaching a point directly to the rear thereof said air currents will be drawn into the path 30 of the forced draft. However, it is to be understood that this back pressure is very minute, in the foregoing devices, as considerable resistance is offered by the blower fan, which resistance increases as the fan continues in operation over a period of time.

35 In this form of the invention the air passages adjacent the panel 16 are preferably provided with a plurality of horizontally disposed louvres 33 which are rigidly secured 40 in the frame 11 and are directed inwardly and upwardly. While these louvres act different than those illustrated in the preferred form of the invention, they serve with similar results for preventing any back flow of 45 air therethrough. The air, siphoned through air passages having horizontally disposed upwardly directed louvres mounted therein, will be directed upwardly into the path of the forced draft.

50 The form of the invention disclosed in Fig. 5 is somewhat similar to that shown in Figures 1 to 3, inclusive. However, in this form, the vertically disposed V-shaped baffle plate 55 and louvres 28 are not employed and the conical baffle member 31 is mounted in place 60 of the former. Louvres 34, comprising flat metallic strips, are angularly mounted in a vertical plane, relative to the side walls of the frame 11, in the air passages for directing 65 air passing therethrough towards said side

walls. As indicated by the arrows in Fig. 5, the passage of air through the device is such that there is no back pressure created along the side walls of the air duct.

5 The vertically disposed strengthening flanges 26 on the panel 16 are, in each of these forms, directed inwardly and centrally thereby providing, in effect, additional baffles for the air currents.

10 While various forms of the invention have been shown in the drawings and described in detail in the accompanying specification, it is to be understood that this device is capable of embodying variations and modifications in detailed structure without departing from 15 the spirit of the invention nor the scope of the appended claims.

I claim:

1. An air circulating device for a furnace, having in combination, a blower fan, a fixed deflector adjacent said blower fan, an air passage on each side of said blower fan for spreading the draft created by said blower fan, and a plurality of fixed deflectors in said air passages.

2. An air circulating device for a furnace, comprising in combination, a frame having a panel mounted therein, a blower fan mounted over an opening in said panel, a deflector adjacent said opening, an air passage on each side of said panel and a plurality of deflectors in said air passages for directing air outwardly of said panel.

3. An air circulating device for a furnace, having in combination, a frame adapted to be mounted in the air intake duct, a panel in said frame, a blower fan mounted on said panel adjacent an opening therein for creating a forced draft therethrough, means in the path of said forced draft for directing 100 the flow thereof towards the walls of said duct, air passages in said frame, and a plurality of vanes in said air passages for deflecting air passing therethrough outwardly.

4. In a furnace, an air circulating device 110 comprising, in combination, a frame, a blower fan mounted in said frame for creating a draft therethrough, a vane in said frame for directing the draft passing therethrough outwardly, air passages in said frame, and a plurality of vanes for directing the flow of air through said air passages.

5. A furnace having an air circulating device mounted therein having in combination, a rectangular frame adapted to be mounted 120 in the air intake duct of said furnace, a blower fan mounted in said frame for creating a forced draft therethrough, means in said frame for directing said draft towards each side of said duct, and a plurality of air 125 passages in said frame having fixed louvres mounted therein for directing air passing therethrough in the same direction as said forced draft.

6. In a furnace, an air circulating device 130

comprising a rectangular frame adapted to be mounted in the air intake duct thereof, a blower fan resiliently mounted on said frame for creating a forced draft therethrough, a vertically disposed baffle mounted in said frame for directing said forced draft towards each vertical side wall of said air duct, and a plurality of air passages in said frame having fixed vertical vanes mounted therein for deflecting air passing therethrough into the path of the forced draft.

7. In combination with a blower fan adapted to be mounted within the air duct of a furnace for creating a forced draft therethrough, means associated with said fan for deflecting the passage of air in said duct; said means comprising a fixed vertically disposed angular baffle plate mounted in the path of said forced draft, and a plurality of fixed angular baffle plates mounted in said duct for directing air into the path of the forced draft.

In testimony whereof I affix my signature at 10 South La Salle Street, Chicago, Illinois.

EMIL ACKERMAN.
